United States Patent Office

Des. 185,067
Patented May 5, 1959

185,067

DIVIDED VEGETABLE DISH

Lancaster P. Clark, Jr., Fairfield, Conn., assignor to Clark Metal Products, Inc., Fairfield, Conn., a corporation of Connecticut

Application December 27, 1957, Serial No. 49,054

Term of patent 7 years

(Cl. D44—15)

Fig. 1 is a top plan view of a divided vegetable dish, showing my new design;

Fig. 2 is a front elevation;

Fig. 3 is a bottom plan view;

Fig. 4 is a vertical sectional view, taken along the line 4—4 of Fig. 1.

I claim:

The ornamental design for a divided vegetable dish, substantially as shown.
